UNITED STATES PATENT OFFICE

CHARLES M. GEARING, OF HARTFORD, CONNECTICUT, ASSIGNOR TO THE NEW
DEPARTURE MANUFACTURING COMPANY, OF BRISTOL, CONNECTICUT, A
CORPORATION OF CONNECTICUT.

GAGE.

1,341,978.

Specification of Letters Patent.

Patented June 1, 1920.

Application filed May 18, 1915. Serial No. 28,999.

To all whom it may concern:

Be it known that I, CHARLES M. GEARING, a citizen of the United States, residing at Hartford, county of Hartford, State of Connecticut, have invented a certain new and useful Gage, of which the following is a full, clear, and exact description, such as will enable others skilled in the art to which it appertains to make and use the same, reference being had to the accompanying drawings, forming part of this specification.

My invention relates to gages and more particularly to gages for gaging and sorting balls such as are used in ball bearings for example.

In gaging and sorting devices as heretofore constructed, and having a gaging-slot with diverging sides along which the articles, as balls, are adapted to travel, a difficulty has been that the articles would wedge in the slot, due to their weight, causing a slow movement of the articles and thus resulting in a slow-speed device. Another and more serious difficulty was that the articles would, due to their weight, be forced, *i. e.*, wedged through the slot too soon, *i. e.*, ahead of the gaging point accurately corresponding thereto, resulting in an inaccurate and unsatisfactory separation of the balls. I have devised a machine, of the gaging-slot type, in which the articles are at all times so supported as to counteract the tractional or wedging effect of gravity during all their travel along the slot whereby the aforesaid wedging effect is eliminated and accurate gaging brought about.

One object of my invention is to provide a gaging-slot gaging device in which the articles are at all times so supported as to counteract the tractional or wedging effect of gravity.

Another object is to provide a device of the character indicated in which although the articles are supported during all their travel against the tractional effect of gravity, the articles are during all of their travel in contact with the sides of the gaging-slot and in position to drop therethrough at the points accurately corresponding to their respective dimensions.

To these ends and also to improve gen-

erally upon devices of the character indicated my invention consists in the various matters hereinafter described and claimed.

In the accompanying drawings

Figure 1 is a side elevation of a gaging machine embodying my invention, certain parts being partially broken away the better to show the construction, portions of the hopper being omitted to economize space and the closure plate being shown in partially retracted position;

Fig. 2 is a top plan view of the gaging portions of the machine illustrated in Fig. 1; and

Fig. 3 is a vertical section substantially on the line 3—3 of Fig. 2, and perpendicular to the inclined plane of the machine.

Although I have illustrated, and more particularly described, my invention as embodied in a machine for gaging spherical steel balls it will be understood that I do not limit myself to such machines.

Referring now to the drawings, conveniently carried upon a base-frame, indicated generally as 1, are two cylindrical gaging-slot-defining elements 2 and 3 which provide the trackway along which the balls 4 to be gaged travel. The travel of the balls is preferably effected by the inclining of the elements 2 and 3 at a suitable angle to the horizontal as illustrated. The elements 2 and 3 diverge slightly and gradually from each other whereby the slot 5 between them increases slightly in width from its forward (upper) end to its back (lower) end. With a slot of this character the balls will of course roll along and upon reaching the points upon the slot corresponding in width to their respective diameters will drop through the slot and thus be gaged and sorted.

At least one of the slot defining elements, as 3, is mounted for rotation about its longitudinal axis, being rotated by any suitable driving mechanism, as that indicated generally at 6. The roller 3 is rotated in a direction to carry its slot defining side upward from the slot, *i. e.*, in the direction of the arrows.

This relative upward travel of the slot defining surface of the roller 3 causes the

roller to exert a lifting effect upon the balls being gaged and the "sinking-through" or wedging effect on the balls caused by the 5
trictional effect of gravity on the balls is thereby counteracted and overcome. The result is accurate gaging even though, as in the present instance, a slot with very gradually diverging sides is employed. Of course the speed of rotation of the roller is 10
preferably such as to exert this lifting effect only to the extent of preventing the "sinking-through" or wedging effect and is not so great as to lift the balls out of accurate gaging contact with the sides of the slot 5.

With a construction such as described it will be seen that each ball will without wedging its way through, or sticking in, the slot travel along the slot up to the 20
gaging point accurately corresponding with such ball's dimensions. Thus inaccuracy due to a ball wedging through the slot under its weight and ahead of its proper gaging point is eliminated and the ball 25
drops through the slot at such proper gaging point. Also because this wedging effect is eliminated the balls will not stick in the slot to reduce their speed of travel and therefore the machine is high-speed. 30
It will be seen that the rotating roller, although it exerts the desired lifting effect, is not, as distinguished from those step-by-step machines in which means are provided for lifting the balls clear of the 35
track, moving them forward a step and again depositing them on the track, of a character which at any time takes the ball from the track to thereby prevent its dropping through exactly at its proper gaging 40
point. On the contrary the roller at all times permits the ball to remain in gaging contact with the track during its entire travel therealong.

By providing a means for propelling the 45
balls wholly distinct from the roller 3, as the inclined frame which causes the ball to be propelled by gravity, it is possible to grind the cylinder 3 accurately to size whereby each of its elements will provide an accurate straight line slot-edge or straight-edge, thus eliminating the practical impossibility 50
of accurate grinding incident to a construction in which a rotating member which serves as a slot-side is constructed, for example, in the form of a screw for propelling the balls.

Preferably a feeding means, indicated 60
generally as 7 and more fully described hereinafter, which feeds the balls to the gaging slot one at a time and slightly separated from each other is employed. The separation of the balls is conducive to accuracy because, even should it occur that each ball did not travel at exactly the same speed 65
as all the others, there would be no chance of

the balls "pyramiding", i.e., of a ball being lifted from the trackway by side pressure from some of the others, such as might occur were a ball in contact with the two at each side of it. I find that the rotating 70
roller 3 aids materially in maintaining the initial separation of the balls throughout their travel.

Thus a machine embodying my invention 75
preferably embodies a pair of gaging-slot-defining elements, as the cylinders 2 and 3, one of which at least, as 3, is in the character of a smooth uninterrupted roller, say a cylinder, adapted for rotation upward away from the slot, such elements, as 80
2 and 3, being arranged to provide a gaging slot with gradually diverging sides, and means, as the inclined frame 1, distinct from the rotating cylinder for causing the travel of the balls along the gaging slot, it being desirable to provide means, as the feed 7, for delivering the balls one 85
at a time and spaced apart to the gaging slot.

In the present embodiment the cylinder 90
2 is carried in clamps 8 and 9 upon the frame 1 which clamps are attached adjustably to the frame proper as by the slot and set-bolt connections 10 and 11. The purpose of the adjustment is, of course, to 95
regulate the width of the slot, the width of the slot being accurately determined in any suitable manner as by temporarily placing the pins *a*, *b* of slightly different diameters between the elements 2 and 3 and 100
bringing the elements into contact with the pins.

For accurate shifting of the clamps 8 and 9 it is desirable to provide each clamp with means such for example as (see Fig. 105
3) the adjusting screw 12 threaded into a fixed part of the structure, as at 13, and passing loosely through the base of the clamp but held against longitudinal travel with respect thereto by the collar 14 fixed 110
to the clamp and fitting in the circular groove 15 of the screw. In order that the clamp may be slid upon the reduced end of the cylinder the base of the clamp may be in two sections splined together as shown, 115
and held by screws 47.

The rotating cylinder 3 is shown as mounted in the journal blocks designated generally as 16 and 17 respectively. Each of these journal blocks is preferably constructed as shown more particularly in Fig. 120
3 wherein the bow-shaped main portion 18 is provided with a projecting contact portion 19 of any desired width longitudinally of the cylinder for bearing upon the roller 3, the movable block portion 20 is provided with similar projecting contact elements 21, 21, for bearing on the roller 3, and set bolts 22, 22, are adapted to force the piece 20 toward the roller 3 and thus bring the 125
130

contacts, or bearing elements proper, 19, 21, and 21 into intimate bearing contact with the roller 3 wherein they, in effect, grind their tracks. The advantage of this 5 construction is that a much more accurate bearing is obtained—one practically without looseness—than an ordinary journal box would provide.

Preferably the roller 3 is driven by the 10 driving gear 6 in mesh with the driven gear 23, the driving shaft 24 and the double universal joint connection 25.

The before referred to ball feed is preferably constructed as follows. The ball delivery pipe 26 is perforated at 27 for the reception of the ball-stop-pin 28 suitably carried as shown (Fig. 1) upon the machine frame. The pin 28 is mounted for sliding movement into and out of the hole 27, as by 15 being carried in the sleeve 29, and is pressed toward the hole 27 by the expanding spring 30. The pin is provided with a shoulder 31 for contact with the reciprocating closure plate 32. The closure plate 32 when in advanced position closes the pipe 26 against the passage of balls but when in retracted position permits, by virtue of the ball aperture 33 (Fig. 2), the passage of balls. For 20 reciprocating the plate 32 it is preferably carried upon an arm 34 oscillatably mounted upon the frame of the machine, as at 35, and carrying a roller or cam-follower 36 received in the endless cam slot 37 of the cam 38, the cam being rotated as by being fast connected 25 with the roller 3.

With the above construction it will be seen that as the cam 38 rotates the plate 32 is reciprocated. When the plate 32 is in retracted position the aperture 33 is in register 40 with the pipe 26, permitting a ball to drop to the gaging guideway. At this time the pin 28 is projected into the hole 27 and holds up the column of balls above it. When the plate 32 advances it closes the pipe and, by 45 virtue of the plate contacting the shoulder 31 of the pin 28, the pin is pushed back permitting the column of balls to move down the pipe the distance of one ball and rest on the plate. When the plate retreats the pin, by virtue of the spring 30, advances and inserts itself between the bottom and the next-to-the-bottom ball and holds up the column 50 except for the bottom ball. The aperture 33 now registers with the pipe and the bottom ball is permitted to drop onto the guideway being guided, if desired, by a supplementary feed pipe sufficiently short to not interfere with full reciprocation, as the illustrated 55 supplementary feed pipe 26'. Thus the balls 60 are delivered to the guideway one at a time and spaced a short distance apart.

Preferably a suitable hopper 39 is provided for containing the balls and may comprise the stationary bottom 40 with its outlet 65 41, the side 42, and the cone-shaped false

bottom 43, the two latter being connected for rotation with the central spindle 44 in any suitable manner and as of course well known in the art, and the spindle 44 being rotated as by the driving connections indicated generally as 45.

Preferably a suitable means, as for example the series of ball receiving pipes 46, is provided below the slot for maintaining the separation brought about by the gaging 75 process.

It will be understood that, although I have illustrated the straight-edge element 2 as a cylinder (that form being preferable as, upon a given portion of the surface becoming worn, the cylinder may be turned slightly in its clamps to bring a new surface into use, thus eliminating the very frequent regrinding incident to mere plain straight-edged strips of material,) I do not restrict 85 myself to that form as any other suitable element giving a straight-edge may be used.

It will also be understood that although I have illustrated a device having but one rotating cylindrical straight-edge element I do 90 not restrict myself to a device having but one rotating straight-edge element.

In the particular machine illustrated and which is more particularly adapted for gaging balls within a limit of .0001 inch I may 95 use a gaging slot about seven inches long and make such slot .001 inch narrower at the forward (top) end than at the back (bottom) end. Of course I do not restrict myself to these dimensions and, indeed, in the present 100 drawings the taper of the slot, in order the better to show the invention, is considerably greater than .001 inch to seven inches.

It will be seen that I have provided a device of the character indicated which is 105 simple, comparatively inexpensive to manufacture, high-speed and capable of great accuracy.

Having thus described my invention, what I claim as new and desire to secure by Letters Patent is—

1. In a device of the character indicated, a pair of gaging-slot-defining elements so located with respect to each other as to provide a gaging-slot, one of said elements being rotatable, means for rotating such element, means for feeding the articles to be gaged to said slot; such means comprising a delivery pipe and a reciprocating closure plate for controlling exit from said pipe; and 115 means operatively connecting said rotative slot-defining-element and said plate and whereby said element during rotation controls the reciprocation of said plate; such last named means comprising a cam connected for rotation with said rotatable element and having its cam surface contoured to reciprocate the follower of said cam during said cam's rotation, an oscillatably mounted arm connected with said plate, and a fol- 120 125 130

- lower for said cam connected with said arm and contacting said cam; substantially as described.
2. In an instrument of precision for gaging articles, a pair of gaging-slot-defining elements so located with respect to each other as to provide a gaging-slot, one of said elements being in the character of a roller with a smooth uninterrupted surface and having its rotational axis extending in the direction of said slot, means for rotating said roller in a direction to cause its slot defining side to travel upward from said slot, means for feeding the articles to said slot one at a time and in separated relation; said roller acting to overcome the tractive effect of gravity upon said articles whereby said articles will not, due to their weights, pass through said slot before reaching the gage points upon said slot accurately corresponding to the respective articles and also acting to preserve the initial separation of the articles brought about by said feeding means whereby each article is given a free travel along said slot free from and uninfluenced by any of the other articles; and such feeding means comprising a delivery pipe and a reciprocating closure plate for controlling exit from said pipe; and means operatively connecting said rotative slot-defining-element and said plate and whereby said element during rotation controls the reciprocation of said plate; substantially as described.
3. In an instrument of precision for gaging articles, a pair of gaging-slot-defining elements so located with respect to each other as to provide a gaging slot, one of said elements being in the character of a roller with a smooth uninterrupted surface and having its rotational axis extending in the direction of said slot, means for rotating said roller in a direction to cause its slot defining side to travel upward from said slot, means for feeding the articles to said slot one at a time and in separated relation; said roller acting to overcome the tractive effect of gravity upon said articles whereby said articles will not, due to their weights, pass through said slot before reaching the gage points upon said slot accurately corresponding to the respective articles and also acting to preserve the initial separation of the articles brought about by said feeding means whereby each article is given a free travel along said slot free from and uninfluenced by any of the other articles; and such feeding means comprising a delivery pipe and a reciprocating closure plate for controlling exit from said pipe; and means operatively connecting said rotative slot-defining-element and said plate and whereby

said element during rotation controls the reciprocation of said plate; such last named means comprising a cam connected for rotation with said rotatable element and having its cam surface contoured to reciprocate the follower of said cam during said cam's rotation, an oscillatably mounted arm connected with said plate, and a follower for said cam connected with said arm and contacting said cam; substantially as described.

4. In an instrument of precision for gaging articles, a pair of gaging-slot-defining elements so located with respect to each other as to provide a gaging-slot, one of said elements being in the character of a roller with a smooth uninterrupted surface and having its rotational axis extending in the direction of said slot, means for rotating said roller in a direction to cause its slot defining side to travel upward from said slot, and means for feeding the articles to said slot one at a time and in separated relation; said roller acting to overcome the tractive effect of gravity upon said articles whereby said articles will not, due to their weights, pass through said slot before reaching the gage points upon said slot accurately corresponding to the respective articles and also acting to preserve the initial separation of the articles brought about by said feeding means whereby each article is given a free travel along said slot free from and uninfluenced by any of the other articles; and such feeding means comprising an article delivery pipe of a cross-section sufficient to accommodate a single-file column of articles and having its open end in delivery relation to said slot, such pipe being provided in the side with an article-stop-pin-receiving aperture, a reciprocatively mounted article-stop-pin arranged for insertion in and withdrawal from said aperture, a reciprocatively mounted closure plate at said open pipe-end and having an article-aperture therein to be moved into and out of register with said pipe-end during reciprocation of said closure plate, and means for reciprocating said pin and plate constructed and arranged to move the imperforate portion of said plate into register with said pipe-end when said pin is retracted and move the article-aperture of said plate into register with said pipe-end when said pin is inserted in said pin-receiving aperture; substantially as described.

In testimony whereof, I hereunto affix my signature, in the presence of two witnesses.
